United States Patent

Des. 236,023
Patented July 22, 1975

236,023

COMBINED PORTABLE FLUORESCENT LIGHT AND POWER PACK THEREFOR

Thomas N. Zelina, Erie, Pa., assignor to
Lighting Systems, Inc.

Filed May 22, 1974, Ser. No. 472,134

Term of patent 14 years

Int. Cl. D26—02

U.S. Cl. D48—24 R

FIG 4.FIG 5.FIG 6.FIG. 1 is an isometric view of the portable fluorescent light and power pack therefor according to the invention with the fluorescent tube supported on the battery case;

FIG. 2 is a front view of the portable fluorescent light and power pack therefor shown in FIG. 1;

FIG. 3 is an end view of the portable fluorescent light and power pack therefor shown in FIG. 2;

FIG. 4 is an isometric view of the portable fluorescent light and power pack therefor shown in FIGS. 1, 2 and 3 with the light removed from its holder;

FIG. 5 is a front view of the portable fluorescent light and power pack therefor shown in FIG. 4; and

FIG. 6 is an end view of the portable fluorescent light and power pack therefor shown in FIG. 4.

I claim:

The ornamental design for a combined portable fluorescent light and power pack therefor, as shown and described.
